SUPERHEAT REGULATOR

Original Filed April 10, 1918 2 Sheets-Sheet 2

BENJAMIN BROIDO INVENTOR.

BY *O. V. Thiele*

his ATTORNEY.

UNITED STATES PATENT OFFICE.

BENJAMIN BROIDO, OF NEW YORK, N. Y., ASSIGNOR TO THE SUPERHEATER COMPANY, OF NEW YORK, N. Y., A CORPORATION OF DELAWARE.

SUPERHEAT REGULATOR.

Original application filed April 10, 1918, Serial No. 227,803. Divided and this application filed December 23, 1920. Serial No. 432,850.

To all whom it may concern:

Be it known that I, BENJAMIN BROIDO, a citizen of the United States, and resident of New York, New York, have invented certain new and useful Improvements in Superheat Regulators, of which the following is a specification.

This application is a division of my application for patent filed April 10, 1918, Serial Number 227,803.

The invention described and claimed herein has reference to so-called regulators, the function of which is to reduce the amount of superheat that has been imparted to steam in the superheater after its generation in the boiler. Since the degree at which the steam is superheated in the superheater will vary from time to time it is necessary to vary the conditions in the regulator if it is desired to maintain the final temperature of the steam constant. The object of the present invention is to provide improved means for varying the regulating effect for the purpose stated.

The invention is illustrated on the two sheets of drawings herewith, where Figs. 1 and 2 show two arrangements respectively, embodying my invention, each of the figures showing the regulator, the portion of the boiler intimately associated with it, and the connections between the two; and Fig. 3 shows on an enlarged scale a valve and its controlling element used in my invention.

Referring first to the form illustrated in Figure 1, the boiler is represented at 1, which may be either the main barrel itself of a boiler or may be the steam and water drum of a water tube boiler. In any event it must include a steam space 2 and a water space 3, but may otherwise be of any form or type whatever.

The steam space 2 and water space 3 are connected to the regulator by means of pipes 4 and 5 respectively. The regulator, itself, is of a type shown in the prior art and may briefly be described as follows. A drum 6 is closed at its two ends by tube sheets 7 and 8. Between these tube sheets extend the tubes 9, which do not open into the space within the drum 6 but do open into the two headers 10 and 11.

The pipe 5 opens into the inside of the

drum 6 at a low point, and the pipe 4 at a high point.

Superheated steam is admitted to the 55 header 11 of the regulator through a pipe 13 and is conducted away from header 10 by a pipe 12. This superheated steam may come from the boiler to which pipes 4 and 5 are connected or from some other source. 60 In any case before being delivered to header 11 by pipe 13 it has been superheated.

In pipe 4 there is the hand-valve 14 and in pipe 5 a hand-valve 15, both of them of any usual or preferred kind. In pipe 4 65 there is in addition a thermostatically controlled valve 16. This valve 16 is of a commercially well-known type and acts in response to variations in temperature, the operative impulse being transmitted to it by 70 pipe 17 from the thermal element 18, which element is located in the pipe 12. The thermostatic valve is arranged to close at a certain predetermined temperature of the element 18, and to be wide open at a second 75 higher predetermined temperature assuming intermediate positions between these two temperatures. The two temperatures will of course have a definite relation to the ultimate desired temperature of the steam as 80 will be clearer from the following description of the operation.

The valve 16 and its co-operating thermostatic element 18 are illustrated on an enlarged scale in Fig. 3. The spring 51 85 tends to keep the balanced valve 50 in housing 37 closed, this tendency being opposed by pressure exerted by the fluid in chamber 52 actuating the valve through rod 53. The pressure in chamber 52 varies with the 90 amount of fluid forced into the chamber, or allowed to leave the chamber, through pipe 39, the other end of which communicates with chamber 54. Fluid is forced from the chamber 54 or allowed to enter it through 95 pipe 39 in response to a rise or a drop respectively of the temperature of element 18. The valve and its control are of a known commercial type and it is not thought necessary to enter further into any detailed description of its construction, as its precise form is not a part of my invention. Its action is such that when the temperature of 100 the steam in pipe 12 falls below a certain

- point, the valve is closed; when said temperature rises above a certain higher point, the valve is wide open; while at intermediate temperatures the valve assumes corresponding intermediate positions. Any thermostatically controlled valve answering these requirements and otherwise suitable may be substituted for the one shown and described.
- 10 The valves 14 and 15 are always wide open during normal operation of the apparatus. With valve 16 wide open, the space within the drum 6 of the regulator will evidently be completely filled with boiler water which 15 will rise in pipe 4 to a level as high as the water level within the boiler. The superheated steam flowing through the tubes 9 will evaporate some of the water within the drum 6 and its temperature will thereby be 20 reduced. The maximum temperature reducing effect possible with the regulator will evidently be obtained when drum 6 is entirely filled with water as just described. Should this reduction bring the temperature 25 of the steam below the constant temperature desired, the thermostatic valve 16 will close. Steam generated by the evaporation of the water in drum 6 can then no longer escape to the steam space 2 of the boiler by way of 30 pipe 4 and will accumulate in the upper portion of drum 6. This will result in a lowering of the water level within the drum 6 and a consequent lessening of the effect of the regulator. Should all of the water be 35 forced out no further regulating effect will occur. If with the water level in drum 6 depressed to any point as described, the resulting temperature of the superheated steam is too high, the thermostatic valve 16 40 will open, permitting steam formed in the drum 6 to escape to the boiler, and more water to reach the regulator through pipe 5. This will result in a greater reduction in the 45 temperature of the superheated steam. The valve 16 will evidently finally assume a certain intermediate position and retain it as long as the temperature of the superheated steam delivered to the regulator remains constant.
- 50 It should be noted that the heat given up by the superheated steam in its passage through the regulator is not lost, but delivered back to the boiler by the steam delivered through pipe 4.
- 55 In the arrangement illustrated in Figure 2, the regulator is by way of variation placed in a horizontal instead of a vertical position, but is of the same construction as that of Figure 1. Pipes 4 and 5 here also 60 connect the steam space and the water space of the boiler with high and low points of the regulator drum respectively, and are also provided with valves 14 and 15. The thermostatic valve 16 is in this variation not in 65 pipe 4 but in the water supplying pipe 5.

Its thermostatic element 18 is also in the pipe 12, delivering the superheated steam after its passage through the regulator.

The operation of this form is as follows. With the valve 16 wide open the entire water space within the drum 6 of the regulator is filled with water which reaches a level in pipe 4 equal to that of the water in the boiler. Under these conditions the maximum tempering or regulating effect is obtained. Should the regulating effect be too great the valve 16 will close to such a point that the rate at which the water is evaporated in drum 6 exceeds that at which fresh water is supplied from the boiler through pipe 5 and valve 16. The water level will therefore fall in drum 6 until the regulating effect is sufficiently reduced. In normal operation the position of valve 6 will again assume some position intermediate between the wide open and the entirely closed one, which it will retain as long as the superheated steam delivered to the regulator remains the same.

It will be evident that some variations might be introduced into the arrangement without departing from the spirit of my invention. For example, the steam may flow in a direction opposite to that spoken of above, so that it enters by pipe 12 and leaves by pipe 13, the thermostat in other words being located in the steam before it is tempered. The regulation then will be based on the temperature of the steam as it arrives at the regulator. This and similar variations are meant to be covered by the appended claims.

What I claim is:

1. In apparatus of the class described, the combination of a boiler, a regulator of the type in which the temperature of the superheated steam flowing through it is lowered by water not in direct contact with it by an amount depending on the amount of water in the regulator, a conduit supplying superheated steam to the regulator, a second conduit conveying it away, a pipe connecting a low point of the water space of the regulator with the water space of the boiler, a pipe connecting an elevated point of the regulator water space with the steam space of the boiler, a valve in the last-named pipe operative responsively to the temperature of the superheated steam to assume a closed position when the temperature falls below a predetermined point, an open position when it rises above a predetermined higher point, and intermediate positions for intermediate temperatures.

2. In apparatus of the class described, the combination of a boiler, a regulator of the type in which the temperature of the superheated steam flowing through it is lowered by water not in direct contact with it by an amount depending on the amount of water in the regulator, a conduit supplying super-

heated steam to the regulator, a second conduit conveying it away, a pipe connecting a low point of the water space of the regulator with the water space of the boiler, a pipe 5 connecting an elevated point of the regulator water space with the steam space of the boiler, a valve in one of the two pipes operative responsively to the temperature of the super-

heated steam to assume a closed position when the temperature falls below a predetermined point, an open position when it rises above a predetermined higher point, and intermediate positions for intermediate temperatures. 10

BENJAMIN BROIDO.
